UNITED STATES PATENT OFFICE.

HAROLD NILSON AND LEONARD NILSON, OF WAYZATA, MINNESOTA.

TRACTION MACHINE.

Application filed February 3, 1918, Serial No. 274,667. Renewed October 3, 1920. Serial No. 415,678.

To all whom it may concern:

Be it known that we, HAROLD NILSON and LEONARD NILSON, citizens of the United States, residents of Wayzata, county of 5 Hennepin, State of Minnesota, have invented certain new and useful Improvements in Traction Machines, of which the following is a specification.

Our invention relates to that type of machine shown and described in our application for Letters Patent of the United States, filed October 9, 1918, Serial No. 260,202, in which the frame of the machine is provided with an upper and a lower rail arranged 10 in a vertical plane, with the operating parts mounted between said upper and lower rails, the frame being mounted to oscillate laterally on horizontal pivots and adjust itself to the inequalities of the ground over which 15 the machine may be moving. In this case our object is to so mount the engine that by loosening a few bolts it can be swung on an axis concentric to the crank shaft to either side of the frame for the purpose of allowing 20 access to the cylinders, the pistons or the valves, or in fact any operating part of the engine.

A further and particular object of so mounting this engine is to do away with 25 the necessity of removing the engine from the frame and remounting it and realigning the parts whenever it is desired to repair or change any of the mechanism.

The invention consists generally in 30 mounting the engine of the tractor so that it will swing laterally to either side of the machine on a bearing concentric with its crank shaft.

In the accompanying drawings forming 35 part of this specification,

Figure 1 is a side view, partially in section, of a traction machine embodying our invention,

Figure 2 is a plan view, showing the engine tilted to one side of the machine frame.

In the drawing, 2 represents the rear traction wheels of the machine and 3 one of the forward guiding wheels. 4 is the lower rail and 5 the upper rail of the frame, 45 formed by bending a channel bar so that its middle portion is substantially upright, while the ends are in substantially parallel relation. This frame may be made of other suitable material, in which the principle 50 herein shown may be embodied. 6 repre-

sents the housing or transmission case having bearings for the rear axle 7 and bolted to the lower rail 4 at 8 and to the upper rail 5 at 9. This housing and the gearing therein forms no part of our present invention and we will not, therefore, enter into a detailed description of it. It is sufficient to say that it has a suitable cover 10 through which access may be had to the gearing. 60 A shaft 11 having a pulley 12 thereon is 65 provided at one side of the frame and has driving connections with the gearing contained in the housing 6.

Coming now to the invention claimed in this case, 13 represents a bell-shaped housing or casting that is secured to the front portion of the housing 6 by suitable means, such as bolts 14. This housing may be detached when the bolts are removed. The housing, as shown in Figure 1, is preferably 70 composed of upper and lower sections for convenience of handling and may be of any other suitable shape that is adapted for this purpose. 15 represents the frame of an engine. It is provided with a bearing 16 at its 75 forward end, concentric with the crank shaft 17 and journaled in a bracket 18 that is secured to the forward portion of the lower rail 4. The crank shaft projects through the rear wall of the housing 15 and is provided with the usual fly wheel 19. A plate 20 has an opening 21 therein for the crank shaft and is secured to the housing 15 by suitable means such as bolts 22. The plate 20, instead of being secured to the frame of 80 the engine by the bolts 22, may be formed integrally therewith. This plate has a flanged edge 23 forming a seat to receive a 85 ring or flange 24 forming the forward portion of the housing 13. Bolts 25 are mounted 90 in sockets provided in bosses on the housing 13 and project through the plate 20 and have springs 26 bearing on said plate and adjusting nuts 27 for regulating the tension 95 of said springs. We prefer to provide the 100 springs 26 to take up any strain or jar on the engine frame and its connections which might result from the sudden lurching or pitching of the machine. When these nuts 105 are tightened, the plate 20 will be locked securely on the flange 24 and the engine frame 13 will be yieldingly held with its crank shaft in line with the shafts of the gear case 6 and in a vertical position between the upper and lower rails of the frame. When, 110

however, the user of the machine wishes to have access to the cylinder or any of the working parts of the engine, he will loosen the bolts 25 and upon removing them from 5 their bearings in the casting 13 the plate 20 will be free to revolve with the frame 15 on the flange 23 and the engine frame may be swung outwardly on either side of the frame to allow convenient access to the operating 10 mechanism for any purpose. The engine may be allowed to swing down until it rests upon the lower rail or any other suitable support may be provided and any or all of the operating parts may then be removed except 15 the crank shaft. When the parts have been replaced, and it is desired to reset the engine in its working position, it will not be necessary to readjust or realign it and its crank shaft, as ordinarily would be the case 20 where an engine is removed from its supporting frame. We are thus able to effect a considerable economy in the time and labor required to readjust or re-fit any of the parts 25 of the engine. As soon as the engine frame has been raised to its normal working position, the bolts 25 are replaced, the plate 20 and the bell-shaped casting rigidly clamped together and the machine is then ready for use.

30 We have shown a bar 28 secured at its ends to the rails 4 and 5, there being one on each side of the frame. These bars have a truss effect for holding the upper and lower rails in their proper relative position.

35 We claim as our invention:

1. The combination, with a traction machine frame, of an engine having bearings in said machine frame concentric with the crank shaft of the engine, one of said bearings comprising a plate secured to the engine frame and a casting mounted on the machine frame and having a peripheral bearing for said plate, and means for locking said casting and said plate together, said locking means, when released, allowing said engine frame to be tilted to one side of the machine frame for exposing the working parts thereof.

2. The combination, with a traction machine frame and a gear casing secured thereto, of a housing secured to said gear case and provided with a flanged peripheral edge, an engine frame having a bearing at one end on the peripheral edge of said housing for rotation thereon when said engine frame is released, means for normally clamping said bearing and said housing together, and a bearing on said machine frame for the opposite end of the engine frame.

60 3. A traction machine comprising a frame having upper and lower rails, and an engine frame supported between said rails, said engine frame being mounted to tilt to either side of said machine frame to expose its working parts, and means for locking said

engine frame in an upright position between said upper and lower rails.

4. A traction machine comprising a frame having upper and lower rails, an engine frame mounted in bearings between said upper and lower rails, said bearings being concentric with the crank shaft of the engine and one of said bearings comprising a plate-like member secured to the engine frame and having a peripheral seat on which said plate is guided in the rotation of said engine frame, and means for locking said engine frame in an upright position between the rails of said machine frame.

5. A traction machine comprising a frame having upper and lower rails, an engine frame journaled at its forward end in the lower portion of said machine frame, a housing mounted between the upper and lower rails of said machine frame and having a flanged peripheral edge, a member secured to said engine frame and having a seat to receive said peripheral edge and on which seat said member is adapted to slide when said engine frame is tilted in either direction, and means for locking said member and said peripheral edge together.

6. The combination, with a traction machine frame having upper and lower rails, of a housing mounted therein, an engine frame seated in said housing for rotation thereon, a bearing for the opposite end of the engine frame concentric with said housing bearing, bolts mounted in said housing and having means for clamping the bearing of said engine and said housing together, said bolts when released allowing freedom of tilting of said engine frame in either direction.

7. The combination, with a traction machine frame having upper and lower rails, of a housing mounted therein, an engine frame seated in said housing for rotation thereon, a bearing for the opposite end of the engine frame concentric with said housing, bearing bolts mounted in said housing and having means for clamping the bearing of said engine and housing together, said bolts, when released, allowing said engine frame to tilt laterally in either direction and compression springs mounted on said bolts for taking up the shock or jar on the engine frame resulting from the lurching of said machine frame.

8. A traction machine comprising a frame, a rear axle mounted therein and traction wheels for said axle, an engine frame mounted in said frame with its crank shaft extending longitudinally thereof, said engine frame having forward and rear bearings concentric with said crank shaft and a driving connection between said engine frame and said traction wheels, means for temporarily securing said engine frame in an upright working position in said machine

frame, said securing means, when released, allowing said engine frame to tilt laterally, for the purpose specified.

9. The combination, with a traction machine frame of greater depth than width, of an engine frame mounted lengthwise of said traction machine frame and having bearings for oscillation of said engine frame to one side of said traction frame to expose 10 the working parts of the engine, and means for normally securing said engine frame in its working position.

10. The combination, with a traction machine frame of an engine frame mounted 15 longitudinally thereof, and having bear-

ings on which said engine frame is adapted to oscillate on either side to expose the working parts of the engine, and means for locking said engine against oscillation.

11. The combination, with a traction machine frame, of an engine frame mounted longitudinally of the machine frame and having bearings in said machine frame for the lateral oscillation of the engine frame to expose the working parts of the engine. 20 25

In witness whereof, we have hereunto set our hand this 27th day of January 1919.

HAROLD NILSON.
LEONARD NILSON.
